UNITED STATES PATENT OFFICE.

WILLIAM K. SMITH, OF PHILADELPHIA, PENNSYLVANIA.

DESIGN FOR A RUG.

SPECIFICATION forming part of Design No. 32,936, dated July 10, 1900.

Application filed June 6, 1900. Serial No. 19,331. Term of patent 7 years.

To all whom it may concern:

Be it known that I, WILLIAM K. SMITH, a citizen of the United States, residing at Philadelphia, in the county of Philadelphia and

5 State of Pennsylvania, have invented and produced a new and original Design for a Rug, of which the following is a specification, reference being had to the accompanying drawing, forming a part thereof.

10 The leading features of my design are: At one end is a representation of a dwelling-house and near the center an open draw-well, with sweep and bucket-chain. By the side of the well is a well-bucket, domestic fowls, mountains in the background, and flowers in 15 one corner, the whole being surrounded by an ornamental border.

Having, as above, fully described my invention, what I claim as new, and desire to secure by Letters Patent, is—20 The design for a rug, as herein shown and described.

WILLIAM K. SMITH.
